UNITED STATES PATENT OFFICE.

GUSTAV E. ESCHER, OF SUMMIT, NEW JERSEY.

MEASURING APPARATUS.

Application filed May 9, 1922. Serial No. 559,633.

This invention relates to improvements in measuring apparatus and especially to apparatus for measuring a plurality of substances simultaneously in the same measure.

5 In the formation of concrete each mix is composed of stone, sand, cement and water mixed in certain proportions. The greatest objection to concrete as a building material is its variation in compressive strength due 10 to the impossibility, in regular practice, of producing concrete in a succession of mixes with a reasonable approach to uniformity of strength. Among other things the strength depends upon the relative quantities of sand 15 and water forming a portion of each mix. As in practice, the sand is never entirely dry, and its bulk varies with its unknown moisture content, it has heretofore been impossible to supply it in uniformly measured 20 quantities and due to its variable unknown moisture content, the amount of water provided has also been variable. I now, therefore, propose to measure the sand by inundation, as set forth in my application 25 Serial No. 536,803, filed February 15, 1922, whereby a substantially uniform measure of sand is provided for each mix and since the moisture content of the thoroughly saturated sand is known, it is only necessary to add 30 to each mix the amount of water necessary to form the complete required amount.

The especial object of the present invention is to provide a simple and efficient measure which will provide substantially uniform 35 amounts of sand and water for each mix, and preferably so constructed that the measured water may be utilized as a washing agent for the measure to assure complete discharge of the sand.

40 For a full understanding of the invention, a detailed description of the invention in its preferred form will now be given in connection with the accompanying drawings forming a part of this specification and 45 the features forming this invention then specifically pointed out in the claims.

Referring to the drawings—

Figure 1 is a side elevation, partly in section, of the complete apparatus;

50 Figure 2 is a vertical sectional view of the measure;

Figure 3 is a section on line 3—3 of Figure 2;

55 Figure 4 is a vertical section of a modified form of the partition shown in Fig. 2;

Figure 5 is a side elevation partly in sec-

tion, of a complete apparatus, with another form of partition and bottom; and

Figure 6 is a horizontal section on the line 6—6 of Figure 5.

In the drawings, discharge pipe 10 of sand storage bin 11 is controlled by a sleeve valve 12 operated by a suitably forked valve rod 13 pivoted on fulcrum arm 14 secured to the bin 11. The discharge from bin 11 60 is preferably distributed by a cone shaped spreader 15 supported by a T-shaped bracket 16 which may be hollow and connected to water supply pipe 17 for delivery of water to the measuring device under control of a hand valve 18. Spreader 15 may be hollow or, as shown in the drawings, the pipe 65 bracket 16 may extend therethrough. Below the bin 11 are provided tracks 19 upon which the measure 20 is supported by wheels 21, 70 journaled in frame 21' on which the measure 20 is pivotally mounted by trunnions 31 carried by brackets 22 secured to the measure. The trunnions 31 are adjustable up and 75 down on the brackets 22 in order to permit the axis through both trunnions to be brought approximately in line with the center of gravity of the measuring device, so that the latter may be tilted readily when dumping it. In the example shown the 80 trunnions 31 are each bolted to the respective brackets by bolts 31^a which pass through slots in the brackets. These slots are indicated at 31^b in Fig. 5. This adjustment 85 need be made only when the capacity of the chambers A and B or either of them is varied as hereinafter explained.

The measure 20 comprises a casing 23, which is divided by a partition 24 into a chamber A, preferably frustro-conical in 90 shape, for the measurement of sand and a tubular chamber B for measuring water, the chambers A and B being connected in any suitable manner as by a plurality of ports 1 in partition 24, preferably arranged in an 95 annular series adjacent the periphery of the partition 24. The ports 1 may be controlled by suitable means which may be included under the generic term separating 100 means to permit the passage of water and prohibit the passage of sand, as in this instance, by a suitable screen and preferably a compound screen 2 which may be composed of a #40 mesh screen on either side thereof. Suitable means are provided for adjusting 105 the size of the chambers A and B which may conveniently be of the form shown, in which

the lower portion of the casing 23 is formed by a plurality of removable casing sections 3, preferably of different sizes, whereby the capacity of chamber B may be satisfactorily 5 regulated by the addition or removal of the requisite casing section. The partition 24, as shown, is removably secured between two of the casing sections 3 and may be secured between any two of such sections for adjustability of chamber A. Chamber B is 10 closed at its bottom by a suitable closure 4, preferably provided with means for breaking the vacuum within the measure 20 during the emptying thereof. For this purpose the closure 4, in the present example, is provided with an opening closed by flanged pipe 5 extending into the chamber B. The inner end of the pipe 5 is suitably recessed to form a seat for a suitable valve, 15 as, for example, the ball valve 6, the play of which may be limited by a suitably ported cap nut 7.

A suitable chute 25 for the mixer, not shown, is located beneath the end of the 20 track 19 which is provided with the usual stop 26 for the wheels 21 of the measure 20. A measure-tilting lever 27 is secured thereto and the measure is held upright in any suitable way, as by a locking dog 28 coacting 25 with a recessed plate 29 secured to the frame 21' and released by handle 30 when the measure is to be tilted.

The operation of the device is as follows:

The hand valve 18 is opened to allow passage of water through T-bracket 16 and spreader 15 to chamber A of measure 20, from which it passes through screened ports 1 into chamber B. When chamber B has been filled completely and chamber A to the 35 requisite percentage of its capacity, which is not less than the percentage of the interstitial space in a given measure of sand, the valve 18 is closed and the sleeve valve 12 is raised by operation of lever 13 to allow the 40 passage of sand from bin 11 to chamber A, whereby the sand is inundated, thus assuring a uniform quantity of sand for each mix. The #40 screen forming a part of the compound screen 2 is of sufficient fineness to 45 prevent passage of sand to chamber B and because of its reinforcement by the $\frac{1}{2}$ " screening is of sufficient strength to support the sand thereon. As the chamber A fills, the water level will move upward therein 50 and when it is completely filled with sand a certain quantity of the water will overflow, this quantity representing the amount of water carried by the sand prior to its delivery to the chamber A as well as any excess 55 originally filled into chamber A. In practice it is advisable to have some excess over the amount necessary to fill the voids in the sand, in order to be sure to have enough. After measure 20 has been filled, it is moved 60 along the tracks 19 and tilted for discharge 65 along the tracks 19 and tilted for discharge 65

into mixing chamber chute 25 for delivery to the mixer. As the measure 20 is tilted ball valve 6 moves away from its seat in the pipe 5 establishing communication between the chamber B and the atmosphere, thus 70 breaking the vacuum within the measure, and assuring discharge of the sand and water. The water in passing from the chamber B acts as a cleaning agent by washing the walls of the chamber A and thus assures 75 delivery of all the sand measured.

In the modification shown in Fig. 4 the partition 24 is shown as valved to prevent the passage of sand to chamber B. For this purpose the partition 24 is provided with a 80 beveled valve seat against which the beveled valve 8 seats. The valve 8 is guided by a plurality of guide rods 9 guided by spider a secured to the partition 24, the opening movement of the valve 8 being limited by heads b 85 carried by guide rods 9. A rod c is secured to the valve 8 and extends upward through the chamber A and preferably beyond the upper end of the measure 20. The valve is 90 preferably provided with a rubber ring 8a forming the valve face, which bears against the seat when the valve is closed. To prevent the trapping of water behind the partition when the measuring device is dumped, the partition has its valve seat portion provided with some holes, as indicated at 24a.

The rod c is raised by hand or through suitable levers to open the valve 8 and allow water to pass to chamber B. When the desired quantity of water has been admitted 100 to the measure 20, the valve 8 is seated, through operation of the rod c, to prevent passage of sand to the chamber B and the sand admitted. When the measure 20 is tipped for discharge, the beveled valve and its seat form an efficient nozzle directing the water in chamber B against the sides of the casing 23 for a thorough cleaning out of the sand.

In Figs. 5 and 6, a modified construction 110 of the lower end of the measuring device is shown. In this construction the lower end is a single cylinder, while the partition and the bottom are arranged to be adjusted up or down in the cylinder, as may be desired. 115 While this may be done in various ways, in the example shown the partition is constructed with a rim 35 which is channel-like in cross-section, and within this channel is located a divided ring 36, on the periphery 120 of which is mounted a packing ring 38 preferably of elastic material, which may project slightly beyond the channel of the rim 35 to contact with the inner wall of the cylinder. Set screws 37 are provided in the vertical wall of the channel to force the ring segments radially outward, thereby forcing the packing ring in tight contact with the inner wall of the cylinder. By loosening 125 these set-screws, the partition may be ad- 130

justed up or down in the cylinder to determine the capacity of the chamber A. The bottom is similarly provided with channel rim, segmental ring, packing ring and set 5 screws. By adjusting it up or down the capacity of the chamber B may be adjusted.

It will be understood that the invention is not to be limited to the specific construction or details shown, as many modifications 10 may be made within the invention as defined by the claims.

What I claim is:

1. A measure for measuring water and sand comprising a casing, a partition dividing 15 the casing into two chambers, means for preventing sand passing into one chamber while providing a passage for water thereto, and means for adjusting the capacity of both chambers comprising a plurality of 20 removable casing sections, the said partition being secured between two of the removable casing sections.

2. A measure for measuring water and sand comprising a casing, a partition dividing 25 the casing into two chambers, a port in the partition connecting the chambers and separating means controlling the port to allow water to pass to both chambers and sand to only one of the chambers.

3. A measure for measuring water and sand, comprising a casing, a partition dividing 30 the casing into two chambers, and having a plurality of ports, and a screen device controlling each port to allow water to pass to

both chambers and sand to one, only, of the 35 chambers.

4. A measure for measuring water and sand comprising a casing, a partition dividing the casing into two chambers, a plurality of ports in the partition connecting the 40 chambers, and a compound screen controlling each port to allow water to pass to both chambers and sand to only one of the chambers.

5. A measure for measuring water and 45 sand comprising a casing, a partition dividing the casing into an upper and a lower chamber, a plurality of ports in the partition connecting the chambers and a compound screen controlling each port to allow water 50 to pass to both chambers and sand only to the upper chamber, the ports being arranged in an annular series near the periphery of the partition to direct the water in the lower chamber against the walls of the upper 55 chamber on tilting of the measure.

6. A measure for measuring water and sand comprising a casing, a partition dividing the casing into two chambers, means for preventing sand passing into one chamber 60 while providing a passage for water thereto, and means for adjusting the capacity of both chambers comprising a plurality of different sized removable casing sections.

In testimony whereof, I have hereunto set 65 my hand.

GUSTAV E. ESCHER.
